UNITED STATES PATENT OFFICE.

FRANK J. MUHLFELD, OF NEW YORK, N. Y.

LARGE-CROWNED HAT.

SPECIFICATION forming part of Letters Patent No. 769,558, dated September 6, 1904.

Application filed July 2, 1904. Serial No. 215,075. (No model.)

To all whom it may concern:

Be it known that I, FRANK J. MUHLFELD, a citizen of the United States, whose residence and post-office address is 1117 Dawson street, 5 borough of Bronx, city of New York, county of New York, State of New York, have invented certain new and useful Improvements in Large-Crowned Hats, fully described and represented in the following specification and 10 the accompanying drawings, forming a part of the same.

The present invention provides an improved means of furnishing a broad-brimmed hat with a crown larger than the head of the wearer 15 and with means for fitting it to the wearer's head to hold it in the desired position.

Heretofore where a crown much larger than the head of the wearer has been desired upon such hats the brim of the hat has been formed 20 with an integral crown or head-band of suitable size to support it upon the head, and a false crown of the required large size has been made separately and fitted over the integral crown and supported to the brim of the hat, 25 thus necessitating the construction of an auxiliary crown of expensive material and adapted to harmonize with the style and texture of the brim.

In the present invention I avoid making 30 such an expensive auxiliary crown by forming the crown of the large size desired integral with the brim and fitting an auxiliary crown-piece to the interior of the integral crown and providing such auxiliary crown-piece with an 35 aperture of suitable size to fit upon the head and support the entire hat. Such crown-piece is formed with a plate or brim of its own extending from the head opening or aperture to the large crown of the hat to fit snugly within 40 the same. The device is not intended to provide ventilation, and therefore does not require perforations or passages between the head - opening and the crown to admit air within the crown. It thus differs from the 45 internal head-band or crown-piece which has been employed in sun-helmets and which is supported or attached to the crown of the hel-

met at a few points only, so that the heat absorbed upon the crown may not be transmitted to the head-band. 50

The present invention is not intended to protect the wearer from heat, but to adapt a large, heavy, and ornamental hat for support upon the head when the crown is made much larger than the head. 55

The crown-piece may be made of cheap or coarse material and covered with any suitable fabric, which may be made to harmonize with the under side of the brim by making such covering of the same or a contrasting color. 60 Other desirable effects may be obtained by covering the auxiliary crown-piece where it is exposed to view with a fine fabric, as plush, velvet, or lace, which may contrast with the under side of the brim, while it furnishes an 65 additional decoration to the hat. Such auxiliary crown-pieces may be readily made of pasteboard and provided at the margin with a perpendicular flange to fit within the hat-crown, and such flange may be made to fit with 70 sufficient tightness within the crown to hold the crown - piece detachably in place. The head opening or aperture in the crown-piece which rests upon the head may be flanged upwardly to increase its stiffness and its bearing-surface upon the head, and a lining-piece 75 of silk or other suitable material may be attached to the edges of the aperture and gathered in the middle to conceal the interior of the large crown. The crown-piece may be 80 made of any material without departing from the invention.

In the annexed drawings, Figure 1 shows in perspective the under side of a wide-brimmed hat with the crown-piece inserted. Fig. 2 85 shows a similar view in section at the center line of the crown, with the crown-piece having a perpendicular flange fitted to the interior of the crown. Fig. 3 is a section of a hat having the crown-piece made in the frustum of a cone. Fig. 4 is a perspective view of such crown-piece. Fig. 5 is a cross-section similar to Fig. 3 with a bell-shaped crown and the crown-piece flanged at the edge only, 90

and Fig. 6 is a perspective view of such crown-piece inverted.

a designates the brim of the hat, which may be of any size and pressed into any desired shape.

b designates the crown, which may be made with perpendicular sides, as in Fig. 2, of bell-shape, as in Fig. 5, or in any other desired shape.

10 *c* designates the plate or body of the crown-piece, (shown in Figs. 1 and 2,) with perpendicular flange *d* at its outer edge to fit within the crown, and an aperture *e*, adapted to fit upon the head to support the hat. The edge 15 of such aperture is shown provided with a small perpendicular flange *f* to stiffen the edge of the aperture and to increase the bearing of the crown-piece upon the hair of the wearer.

The crown is shown in Figs. 1 and 2 eccentric to the brim, and the aperture is shown eccentric to the margin of the crown-piece, as that is the prevailing style; but the crown and aperture, or either of them, may be made concentric, if desired.

25 Fig. 3 shows a crown-piece *c'* of flaring shape like the frustum of a cone, the larger end of the frustum being proportioned to fit within the crown *b* and the smaller end being proportioned to fit upon the head of the 30 wearer.

A gathered lining *g* is shown in Figs. 2 and 3 attached to the margin of the opening and its inner edge drawn closely together to form a lining for the aperture and conceal the 35 interior of the crown.

40 Fig. 5 shows a crown *b'* of bell-shape and the crown-piece made similar to that shown in Fig. 2, with the flange *d* at the margin fitted snugly to the smaller part of the bell-crown, so as to wholly close the inner opening of the 45 crown; but the aperture *e* is unprovided with the strengthening-flange *f*.

50 In Fig. 2 the crown-piece is shown covered upon its outer side with a layer of fabric *h*, which is also extended inwardly over the flanges *d* and *f*. Such fabric may be pasted or sewed to the body and flanges of the crown-piece. If the fabric be made of woven or 55 felted texture, its frictional engagement with the interior of the crown serves very powerfully to hold the crown-piece within the crown. The crown-pieces shown in Figs 3 and 5 are represented without any covering layer *h*, and the crown-piece may be used with or without the covering, as may be preferred.

60 The subject of this invention is readily distinguished from the linings and sweats of various kinds that have been fitted within the crown of a hat, as the crown-piece in the present construction adapts the hat to be manufactured with a crown very much larger than the head upon which it is to be worn.

The crown-piece is also distinguished from the bandeau, which are sometimes applied to or projected from the aperture within a hat-crown to support the hat more firmly upon the head.

65 My crown-piece is distinguished from all the previous fixtures that have been applied within the crown of a hat by having a flange like a brim, which extends from the head opening or aperture *e* to contact with the interior of the crown to which it is applied. It is immaterial whether the crown-piece be made detachable or not.

70 Having thus set forth the nature of the invention, what is claimed herein is—

1. A hat comprising a crown and brim the crown having a relatively large opening, and a separate crown-piece having a flat plate 80 with its outer edge constructed to engage throughout its entire periphery the interior of the hat-crown and provided with an opening to fit the head of the wearer, substantially as shown and described.

85 2. A hat comprising a crown and brim the crown having a relatively large opening, and a crown-piece having an upturned flange on its outer edge to engage the interior of the 90 hat-crown and an opening to fit the head of the wearer, substantially as herein set forth.

3. A hat comprising a crown and brim the crown having a relatively large opening, a crown-piece having an upturned flange on its outer edge to frictionally engage the interior 95 of the hat-crown and an opening to fit the head of the wearer, substantially as herein shown and described.

4. A hat comprising a crown and brim the crown having a relatively large opening, and a separate crown-piece having its outer edge constructed to engage the interior of the hat-crown, and the plate of the crown-piece being set flush with the under side of the hat-brim, substantially as shown and described.

100 5. A hat comprising a crown and brim the crown having a relatively large opening, and a crown-piece having an upturned flange on its outer edge to engage the interior of the 110 hat-crown, and an opening to fit the head of the wearer, the edge of the upturned flange contacting with the top of the crown to support the entire weight of the hat, substantially as shown and described.

115 6. A hat comprising a crown and brim the crown having a relatively large opening, a crown-piece having an upturned flange on its outer edge to engage the interior of the hat-crown and an opening to fit the head of the 120 wearer, and the plate of the crown-piece being made of coarse material and its surface covered with finer material of ornamental character, substantially as shown and described.

7. A hat comprising a crown and brim, the

crown having a relatively large opening, a crown-piece having an upturned flange on its outer edge to engage the interior of the hat-crown and an opening to fit the head of the wearer, and the plate of the crown-piece being finished to contrast with the under brim of the hat, substantially as shown and described.

In testimony whereof I have hereunto set my hand in the presence of two subscribing witnesses.

FRANK J. MUHLFELD.
